PROCESS FOR THE ELIMINATION OF
HEAVY ALKYLATE

Charles C. Chapman, Bartlesville, Okla., assignor to Phillips Petroleum Company, a corporation of Delaware
Filed Apr. 16, 1962, Ser. No. 187,481
1 Claim. (Cl. 260—683.49)

This invention relates to the catalytic production of higher-boiling hydrocarbons. More particularly, this invention relates to a method for the operation of an alkylation system wherein the heavy alkylate produced therein is treated with isoparaffin in the presence of catalyst to produce additional light alkylate therefrom. In one aspect this invention relates to a method of operation of an HF alkylation system to increase the yield of light alkylate and improve the alkylate quality by separating the total alkylate into a light and heavy alkylate and then recycling the heavy alkylate to extinction. In another aspect of this invention there is provided a method of operating an alkylation system so as to alkylate olefins with isopentane in a primary alkylation zone in a manner so as to avoid the accumulation of heretofore insoluble heavier alkylates generally produced in same.

In many processes which have been proposed for converting low-boiling hydrocarbons into higher-boiling hydrocarbons such as the production of motor fuels and lubricants from less viscous, more volatile, normally gaseous hydrocarbons, there is generally produced a portion of the initial reactants which has a boiling point higher than that generally preferred for compounds which possess good motor fuel properties. The total alkylate (butane-free) is generally composed of about 70 percent light alkylate and is that portion having an end point below about 260° F., and about 30 percent heavy alkylate is that portion having an initial boiling point of about 260° F. The light alkylate has an octane rating higher than that of the heavy alkylate.

In addition, while alkylation with isopentane is well known, the process is not generally practiced due to the excessive amount of heavy alkylate of low quality which is produced.

I have now found in accordance with the present invention that such heavier higher-boiling alkylate materials may be avoided by the separation of the alkylate from the reactor and recycling the portion of same boiling above the desired temperature with additional isoparaffin and catalyst. Such recycling serves to increase the overall amount of light alkylate and increases the octane rating of the resulting total alkylate.

Thus it is an object of this invention to produce higher-boiling paraffin hydrocarbons by the alkylation of lower-boiling paraffins in such a manner as to give optimum yields of the desired alkylate fraction.

Another object of this invention is to provide a method for utilizing, while achieving removal of, undesirable portions of alkylate material from an alkylation system.

A still further object of this invention is to provide a desirable method for achieving alkylation using isopentane in such a manner as to avoid the accumulation of heavy alkylate which is normally experienced in the reaction.

Other aspects, objects and the several advantages of my invention and process will be found in the accompanying disclosure, drawing and appended claim.

As shown in the accompanying figure, which is illustrative of one embodiment of this invention, olefin is introduced by means of conduit 1 into alkylation zone 2. Fresh isobutane is added to the alkylation zone 2 by

2

means of conduits 3 and 4. Hydrocarbon reaction effluent is removed from alkylation zone 8 by means of conduit 5 to fractionator 6 wherein the propane and lighter content is removed overhead and isobutane and heavier components are passed by means of conduits 7 and 8 to deisobutanizer 9. Recycle isobutane is removed overhead and returned by conduits 10 and 4 to alkylation zone 2. The residue of deisobutanizer 9 is passed by means of conduit 11 to debutanizer 12 wherein *n*-butane is taken overhead by means of conduit 13 and the remaining alkylate product is passed by means of conduit 14 to alkylate splitter 26 wherein a separation of the heavy and light components is achieved. Generally, the portion boiling below 260° F. is removed as overhead by means of conduit 15 and the portion boiling above 260° F. is removed as bottoms through conduit 16. The specific separation of heavy and light portions may be altered depending on the particular components desired. The bottoms product is returned by means of conduits 16 and 17 to a second alkylation zone 18 wherein additional isobutane is added by means of conduit 19. Make-up HF is introduced by way of conduit 20 and spent HF for rerun is removed by means of conduit 21. A similar provision is made on alkylation zone 2 in conduits 23 and 24 so as to allow the requisite HF catalyst to be introduced into and removed therefrom. Hydrocarbon reactor effluent from alkylation zone 18 is removed by means of conduit 25 and combined with the bottoms product from depropanizer 6 and introduced into deisobutanizer 9 wherein the heretofore described separation is carried out. In this manner the heavy alkylate produced in alkylation zone 2 is continuously circulated for consumption in alkylation zone 18 until extinct, and the heavy alkylates are ultimately removed, after being converted to light alkylate, as light alkylate through conduit 15 of splitter 26.

As another embodiment of this invention, if desired, other higher-boiling paraffin hydrocarbons not derived from the HF alkylation such as a raffinate from the catalytic reforming of naphtha may be added to the heavy alkylate to alkylation zone 18 by means of conduit 28. This raffinate is a paraffinic (and isoparaffinic) portion of reformate from a reforming operation wherein a naphtha charge stock boiling in the range of about 150–400° F. is reformed, using any of the well-known reforming processes, e.g., the Platforming process. The raffinate produced from the reformate is obtained by solvent extraction, using any of the well-known solvent extraction processes, e.g., Udex, to produce a highly aromatic extract and the above-referred-to raffinate which is added to alkylation zone 18. While somewhat more dilute concentration may be used, I prefer to use HF acid in concentration greater than 80 percent by weight, the other material being acid soluble oil, water, dissolved hydrocarbons and fluorides. Also substantially 100 percent hydrofluoric acid, that is substantially or completely anhydrous hydrofluoric acid or hydrogen fluoride, is very effective and is particularly adapted to the process. The process is generally carried out with the hydrocarbon material substantially in liquid phase; efficient reaction results when sufficient hydrofluoric acid is employed to result in a substantial saturation of the liquid hydrocarbon material with hydrogen fluoride, and preferably sufficient hydrogen fluoride is used to form a separate liquid phase which may be maintained, emulsified or intimately mixed with the hydrocarbon while reaction takes place. In most cases the hydrofluoric acid charge should be at least 10 percent of the total charge on a liquid volume basis;

HF acid to hydrocarbon volume ratios range from about 1:10 to 2:1.

The reaction temperature may be varied over a wide range for any particular reaction mixture but appears to be more dependent upon the paraffin hydrocarbon participating in the reaction. Thus, in general, I may carry out an alkylation process at temperatures between 0 and 300-400° F. For readily reacted paraffin hydrocarbons such as isobutane or isopentane a readily effective alkylation temperature is in the range of about 75-180° F.; and for less reactive paraffins, higher temperatures are necessary. The use of hydrofluoric acid has a distinct advantage in such cases in that it can be used under these more extreme conditions without promoting or entering into extensive undesirable side reactions.

Olefins of a wide range of molecular weights and structures are suitable for use in the alkylation of paraffins in the presence of concentrated hydrofluoric acid. One of the principal commercial applications is the production of paraffin hydrocarbons in the motor fuel range from lower-boiling hydrocarbons. For this reason olefins of 5 or fewer carbon atoms per molecule are more often preferred. Of these, ethylene enters into a reaction less readily, especially in the absence of olefins of more carbon atoms per molecule. Propylene and/or butylenes are the preferred olefins. While pentenes are generally considered to be in the motor fuel boiling range, it will often be desirable to decrease the amount of C₅ hydrocarbons in the final product for reasons of volatility or a higher-boiling fuel of low vapor pressure may be desired, so that it will not be unusual to use pentenes. Hexenes, heptenes, octenes and the like are more often of greater value, although they are not to be excluded from the concept of this invention.

Ordinarily the process is operated in liquid phase under moderate superatmospheric pressure such as between about 20 and 200 pounds per square inch gauge. Since the alkylation reaction represents a decrease in the total number of molecules, a certain amount of pressure favors the reaction. However, since the reactants are generally readily maintained in liquid phase with only moderate pressure, using a reaction temperature in the lower part of the range indicated, only sufficient pressure to insure liquid phase operation is generally adequate. When higher reaction temperatures are used, higher pressures may also be used, and pressures as high as 1500-2000 p.s.i.g. or more may be used if desired. While such high pressures favor reaction, lower pressures are generally successfully used with the pronounced activity of hydrofluoric acid to induce the alkylation reaction. Since very moderate temperatures usually suffice in the presence of hydrofluoric acid, for thermodynamic reasons the pressures can accordingly be moderate and can of course be low, as can be shown by trial, to permit effective alkylation. In most instances, the process will be operated under a pressure between 50 and 500 p.s.i.g.

The reaction period during which olefin is introduced, reacted and consumed to produce eventually an isoparaffinic product is determined to a certain extent upon the reaction temperature and the total amount of olefins reacted. A period between 35 seconds and 2 hours has been found satisfactory in most cases.

The following example serves to further illustrate this invention.

Example

Olefin charge (1)—(50-50 propylene-butylens),
b./h. ----- 100
Fresh isobutane (3), b./h.* ----- 190
Recycle isobutane (10), b./h.** ----- 1110 70

Alkylation zone 2:

	Isobutane/olefin volume ratio -----	10:1
	HF/hydrocarbon volume ratio -----	1:1
5	Pressure, p.s.i.g. -----	150
	Temperature, ° F. -----	100
	Product (7), less iC ₄ and nC ₄ , b./h. -----	^a 170
	Research octane w./3 cc. TEL of (170 b./h.) -----	102.0

Alkylation zone 18:

10	Heavy alkylate (less recycle) (17), b./h. -----	50
	Conversion per pass, percent -----	85
	Isobutane (19), b./h.*** -----	300
	Isobutane/olefin volume ratio -----	6:1
	HF/hydrocarbon volume ratio -----	1:1
15	Pressure, p.s.i.g. -----	150
	Temperature, ° F. -----	150
	Total light alkylate (15) (260° F. end point), b./h. -----	220
20	Research octane number (15), w./3 cc. TEL -----	104.0

^a 120 b./h. light alkylate (260° F. end point) and 50 b./h. heavy alkylate (260° F. initial B.P.).

*Includes 70 b./h. for alkylation zone 18 and 120 b./h. for alkylation zone 2.

**Includes 230 b./h. for alkylation zone 18 and 880 b./h. for alkylation zone 2.

***Includes 230 b./h. recycle isobutane.

When isopentane is the isoparaffin charged to the alkylation zone 2, the ratio of light alkylate to heavy alkylate by volume produced therein is about 60 to 40. The heavy alkylate of this operation is then converted into light alkylate in alkylation zone 18 using isobutane as the isoparaffin.

Reasonable variation and modifications can be made in accordance with this invention, the essence of which is that there has been provided a process for producing a maximum quantity of higher octane light alkylate in an HF alkylation which comprises initially alkylating an olefin with an isoparaffin, separating the resulting total alkylate into a light and heavy fraction, treating said alkylate fraction with additional isoparaffin in the presence of HF catalyst, separating the resulting mixture into a light and heavy fraction, and returning said heavy fraction for additional treatment with said isoparaffin and HF catalyst.

I claim:

A process for the elimination of heavy alkylate in an HF alkylation system which comprises introducing into a first alkylation zone maintained at alkylation conditions an alkylatable paraffinic hydrocarbon and an alkylating olefinic hydrocarbon, introducing into a second alkylation zone maintained at alkylation conditions the raffinate obtained from the catalytic reforming of a naphtha stock and the heavy alkylate derived from the fractionation of the combined effluents from said first and second alkylation zones, combining the resulting effluents from said first and second alkylation zones, separating the resulting combined effluents into the light alkylate and heavy alkylate components thereof, returning the separated heavy alkylate component as feed to said second alkylation zone, and thereafter recovering the light components as a product of the process.
